PROTECTIVE PAD FOR PLAYPENS
OR CRIBS

Elaine F. Malm, St. Paul, Minn.

Application July 3, 1950, Serial No. 171,809

7 Claims. (Cl. 5—93)

1

My invention relates to an improvement in protective pad and deals particularly with a type of pad suitable for protecting the rail of a play pen or crib.

Babies are usually confined within cribs or play pens during a considerable portion of the time. These cribs and play pens usually include slatted walls having encircling rails at their upper ends. When such babies are first able to stand up by themselves, they usually support themselves by grasping the railing or the slotted walls to hold themselves upright. Occasionally they fall against the rails and are injured thereby. Thus it has been found important to provide a means of padding these rails so that such injury can not occur.

An object of the present invention resides in the provision of a padding particularly adapted for use on rails and more particularly on rails encircling play pens, cribs and the like. This padding is mainly designed to protect the head of an infant in the event the infant should fall against the rail.

A feature of the present invention resides in the provision of a rail pad which is sanitary and which may be removed and washed or cleaned from time to time. As the device is particularly designed for use on cribs or play pens it is important that the device be easily cleaned. My pad is so designed that it may be detached in an extremely short period of time and may be washed or dry cleaned, depending upon the particular type of material used in its formation.

A feature of the present invention resides in the provision of a pad including a resilient pad body enclosed within an outer sheathing of fabric. The fabric covering is designed to encircle the rail of the crib or bed and to be held in this position by snaps or other detachable fasteners. These snaps or fasteners are spaced to extend between the slats of the crib or play pen so as to hold the padding bent into U-shaped form over the upper surface of the rail.

A further feature of the present invention lies in the provision of a padding which is attractive to the eye and which acts as a decoration as well as a protection for the infant. In preferred form my pad includes a ruffle extending along the outer surface thereof which lends a pleasing appearance to the crib or play pen and serves as a decoration therefor.

These and other objects and novel features of my invention will be more clearly and fully set forth in the following specification and claims.

In the drawings forming a part of my specification:

2

Figure 1 is a perspective view of a play pen showing my protective pads supported thereupon.

Figure 2 is a perspective view of a section of my pad showing the construction thereof.

The pads A are designed for attachment to a crib or to a play pen such as that illustrated in general by the letter B. Such devices usually include a base or bottom frame 10 having connected thereto a series of upwardly extending slats 11. The frame 10 is shown as a solid rectangular element to provide a front for the pen. In many forms of construction the frame 10 merely comprises a rectangularly arranged series of frame strips so that the pen may be folded up and stored when not in use.

The spaced slats 11 support rectangular arranged rails 12 which provide the upper frame work connecting the various slats and forming the rectangular enclosure. The manner in which the rails 12 are connected is not important in the present invention, it being obvious that each side may be provided with a separate rail hingedly connected to the other rails or the rails may be permanently connected at the corners. When the pads A are used in conjunction with a crib, such cribs are often provided with vertically slidable side portions which include spaced vertical slats connected at their upper ends with a rail similar to the rails 12. As all of this structure is well known in the art, there is believed no need for a detailed description.

The pad which I employ includes an inner padding strip 13 which is formed of foam rubber or other suitable material. This strip 13 is merely a rectangular elongated strip of suitable resilient material of necessary thickness to properly cushion the rails 12. The pad 13 is connected along its upper surface by a covering 14 and is enclosed along its undersurface by a lining 15. The covering 14 and lining 15 are preferably substantially wider than the strip 13.

In the form of construction illustrated the cover 14 and lining 15 are connected at 16 by a row of stitching. This stitching 16 connects the members 14 and 15 at points spaced from the marginal edges thereof. The marginal edges 17 and 19 of the covering 14 and liner 15 are folded inwardly and are connected by the concealed stitches 20.

The covering and liner 14 and 15 are also connected by a row of stitching 21 spaced from the other edges of these members. The marginal edges 22 and 23 of the covering and liner respectively are folded inwardly and are connected by the concealed stitching 24. The space be-

tween the row of stitches 16 and the adjacent edges of the members 14 and 15 form a flap 25 useful in holding the pad in proper formation. The area between the stitches 21 and the adjacent edges of the members forms a second opposite flap 26 which also provides a means of holding the pad in place.

A series of snap fasteners are provided along the length of each pad A. These snap fasteners are shown as having male portions 27 and co-operable female portions 29 which snap together under spring tension. The width of the pad and the spacing of the snap fastener portions 27 and 29 is such that when the snap fasteners are engaged the resilient pad 13 is held in inverted U-shaped form over the rails 12. The snap fasteners are preferably spaced to engage between the spaced slats. However, in order that the pad be adaptable for various constructions, the snap fasteners may be positioned at rather short intervals so as to provide the necessary engagement between the edges of the pad regardless of the spacing between the slats.

In preferred form of construction ties 30 are provided at each end of each pad. These ties 30 include one part stitched to one flap 25 and another tie section stitched to the other flap 26. If preferred the ties may be anchored by the stitching 16 and 21, either inwardly of the liner 15, or outwardly of the covering 14. These ties are designed to extend about the end slats of the series to hold the pad from longitudinal movement along the rail. These ties may be eliminated if the pad is produced in elements of considerable length and cut to the proper length to fit each individual installation. However, the use of such ties 30 is preferred, particularly where the pads are made for a crib or play pen of a particular style.

In order to improve the appearance of the padding and to conceal the fasteners fastening the pads together, I provide a ruffle 31 connected to the pad along the line of stitching 21. This ruffle 31 is preferably provided with a folded edge 32 connected to the pad by the stitching 21. Also in preferred form the free edge 33 of the ruffle 31 is folded in a manner to conceal the edge and stitched at 34 to form a finished appearance to the ruffle.

In applying the pad A to the crib or bed, it is only necessary to extend the pad over the rail so that approximately the lateral center of the pad 13 is directly above the rail. The flaps 25 and 26 are next folded downwardly on opposite sides of the rail and the snap fasteners 27 and 29 fastened so as to hold the pad in rail encircling position. During this action the pad 13 is bent into inverted U-shaped form to enclose the upper edge and inner and outer sides of the rails 12.

I have found that my pads A have been extremely effective in preventing injury to children and may be made at a sufficiently low price to make them commercially practical. By leaving the ends of the coverings open, or by leaving at least one end of the covering disconnected, the pad 13 may be withdrawn and the remainder of the padding may be washed or dry cleaned. The task of attaching or detaching the pad is extremely simple and can be completed in an extremely short period of time.

In accordance with the patent statutes, I have described the principles of construction and operation of my protective pad construction for play pens or cribs, and while I have endeavored

to set forth the best embodiment thereof, I desire to have it understood that obvious changes may be made within the scope of the following claims without departing from the spirit of my invention.

I claim:

1. A padding structure for use in conjunction with an elongated rail having spaced slats connected thereto, the structure comprising an inverted U-shaped body of soft resilient material extending over the sides and top of the rail and an enclosing covering enclosing the body and connected together between the spaced slats, said covering including a flap on either side of said body.

2. A protective pad including an elongated strip of soft resilient material, a tubular covering for said strip including a covering member having a liner of fabric, a row of stitching connecting said covering and liner together on each of the opposite sides of said pad, each of said rows of stitching being spaced from the adjacent marginal edges of the covering and liner, and fastener means connected to said liner between said rows of stitching and the adjacent marginal edges of the liner, said fasteners including opposed co-operable elements.

3. The structure described in claim 2 and in which the marginal edges of the liner and covering member are connected together.

4. The structure described in claim 2 and including a ruffle connected to said covering member at a point spaced from one of the marginal edges thereof, said ruffle extending beyond the adjacent marginal edge of the covering member.

5. A pad for protecting a rail, the pad including an elongated body of flexible resilient material, a tubular enclosure for said body, including a liner and a covering member secured together at the marginal edges thereof, said liner and covering member being substantially wider than said body, means connecting said liner and covering member together along a line parallel to, and spaced from, the adjacent edges of the liner and covering member, and co-operable snap fastener portions secured in transversely aligned relation to said liner between the marginal edges and the adjacent fastening means.

6. The structure described in claim 5 and including a ruffle secured to said covering at a point spaced from a marginal edge thereof, said ruffle projecting beyond the adjacent marginal edge of the cover member and liner.

7. A padding structure for use in conjunction with an elongated rail having spaced slats connected thereto, the structure comprising an inverted U-shaped body of soft resilient material extendable over the sides and top of the rail, an enclosing covering enclosing the body, and co-operable fastener elements associated with said covering adjacent opposed edges of said body, said fastener elements when fastened extending between adjacent slats to detachably maintain said body in said U-shaped relation.
